LINE TRIP OR SLUG GUIDE

Filed Sept. 29, 1925

Patented Feb. 8, 1927.

1,616,888

UNITED STATES PATENT OFFICE.

HENRY H. COGHILL, OF RICHMOND, VIRGINIA, ASSIGNOR OF ONE-HALF TO JAMES P. BOONE, OF RICHMOND, VIRGINIA.

LINE TRIP OR SLUG GUIDE.

Application filed September 29, 1925. Serial No. 59,339.

The invention has for its object to provide a simple and efficient line trip or slug guide attachment for type-setting machines whereby the type lines or slugs will be effectively held against tipping when ejected from the trimming knives and thereby caused to properly fall by gravity along the guide channel to the galley without danger of transposition.

The invention further seeks to provide a device of the type stated that is so constructed that it may be readily attached to standard machines without alterations, which will accomplish its intended purpose without in any way marring the face of the type and which may be readily adjusted for use in connection with varied sizes of type lines, the structure being such that all intended adjustments may be quickly and conveniently made and, when so made, not subject to inadvertent variation due to vibration or jarring.

With the above and other objects in view that will hereinafter appear the invention further resides in the novel details of construction, combination and arrangement of parts, all of which will be first fully described, then be particularly pointed out in the appended claims, reference being had to the accompanying drawing, in which:—

Figure 1 is a perspective view illustrating the application of the invention.

Figure 2 is a horizontal cross section of the attachment.

In the drawing, in which like numerals indicate like parts in all of the figures, 1 indicates the slug guide bracket of a type-setting machine, and 2 a portion of the slug ejector, through the medium of which the slugs are forced through the knives (not shown) into the guide or trough-way of the bracket 1 to properly slide down onto the galley 3. A portion of the machine framing is indicated at 4 and serves as a means for supporting the device which forms the subject matter of this invention. The parts thus far described are commonly used in the now standard type-setting machines and their construction and operation is well understood by those skilled in the art.

In carrying out my invention I provide a dovetail guide bar 5 which is secured to the framing portion 4 in vertical position adjacent to and parallel with the trough-way of the bracket 1 by a single securing screw 6 which passes through a countersunk

aperture in the said bar and enters a suitable tapped aperture in the said framing portion. The securing screw 6 and the tapped aperture therefor in the framing portion 4 may be specially provided where necessary but in most standard type-setting machines such a provision will be unnecessary as it will only be necessary to utilize one of the screws and tapped apertures already provided in that framing portion.

The bar 5 has its front face provided with a plurality of closely equi-distantly spaced face depressions 7, the purpose for which will soon appear.

A slide block 8 provided with a dovetail guide groove 9 adapted to slidably receive the bar 5 is mounted upon that bar and is bored as at 10 to receive a ball bearing 11 and a suitable spring 12 positioned for yieldably forcing the ball into certain ones of the depressions 7. As before stated, the block 8 is slidably mounted upon the bar 5 and by reason of providing the depressions 7 and spring pressed ball 11 the block may be freely moved to any position throughout the length of the bar 5 and suitably held to any adjusted position by the yieldable coaction of the ball 11 and the selected depression 7.

An angled member 13 has one arm thereof removably screw-secured, as at 14, to the side of the block 8 adjacent the guide bracket 1, and the other arm thereof projects across the front edges of the guide bracket 1 in position for being engaged by the upper end of any of the slugs ejected into the bracket guideway that may tend to tip forwardly and thus be transposed in transit to the galley. The arm last mentioned has that face thereof presented toward the ejected slugs faced with a wear or abutment plate 15 of leather or any other suitable shock absorbing material such as will accomplish its slug edge engaging function without danger of defacement. The plate 15 is preferably cemented to the arm of the angle member so that no metallic connecting mediums will be presented to the edge of the ejected slugs.

By providing a structure, as before described, means is provided for engaging the upper end of slugs as they are ejected into the guide bracket guideway to prevent all tendency of tipping forwardly and becoming transposed in transit to the galley, the slug engagement being such that the anti-tipping action is positive but is accom-

plished in such manner that all danger of defacing the type edge of the slug is eliminated. The manner of mounting the block 8 and the ball and depression combination 11 and 7 provides for suitable vertical adjustment of the block 8 to position the same for effecting an engagement of the upper ends of varied lengths of slugs, the adjustment being possible without removal or 10 actuation of any screws or other mechanical devices and without the use of such friction devices as would be readily thrown out of adjustment by vibration or shock. The engagement of the ball 11 in the selected depression is such that while the action is yieldable the block 8 will be so held to its adjusted position that there is no danger of the same being thrown out of adjustment by the ordinary vibration and shock incident to the operation of the type-setting machine upon which a device is mounted.

From the foregoing description, taken in connection with the accompanying drawing, it is thought that the novel details of construction, the manner of operation and the advantages of my invention will be readily apparent to those skilled in the art to which it relates.

What I claim is:

30 1. A device of the class described comprising a guide adapted to be secured upon a type-setting machine adjacent the slug-guide bracket thereof and having depressions in one face thereof, a block slidable along the guide and having a spring pressed member for engaging certain of the guide face depressions to hold the block at adjusted positions, and a member carried by the block in position for extending across the slug-guide bracket to prevent tipping of slugs ejected into the bracket.

40 2. A device of the class described comprising a guide adapted to be secured upon a type-setting machine adjacent the slug-guide bracket thereof, and having depressions in one face thereof, a block slidable along the guide and having a spring pressed member for engaging certain of the guide face depressions to hold the block at adjusted positions, a member carried by the block in position for extending across the slug-guide bracket to prevent tipping of slugs ejected into the bracket, said member having a shock absorbing facing for encountering the ejected slugs.

50 3. A device of the class described comprising a guide adapted to be secured upon a type-setting machine adjacent the slug-guide bracket thereof and having depressions in one face thereof, a block slidable along the guide and having a spring pressed member for engaging certain of the guide

face depressions to hold the block at adjusted positions, and an angle member having one arm removably secured to the block and the other arm extending across the slug-guide bracket and having a shock absorbing facing cemented thereto in position for engaging slugs ejected into the bracket to prevent tipping or defacement thereof.

4. A device of the class described comprising a dovetail guide adapted to be secured by a single screw to the framing of a type-setting machine adjacent the slug-guide bracket thereof and having depressions in one face thereof substantially throughout its length, a block slideable upon the dovetail guide and having a dovetail groove to fit said guide and a bore merging with the said groove, a ball in the said bore and a spring for forcing the same into engagement with the depression-provided guide face to provide for yieldable adjustments of the block along the said guide, and a member carried by the block in position for extending across the slug-guide bracket to prevent tipping of slugs ejected into the bracket.

5. A device of the class described comprising a dovetail guide adapted to be secured by a single screw to the framing of a type-setting machine adjacent the slug-guide bracket thereof and having depressions in one face thereof substantially throughout its length, a block slideable upon the dovetail guide and having a dovetail groove to fit said guide and a bore merging with the said groove, a ball in the said bore and a spring for forcing the same into engagement with the depression-provided guide face to provide for yieldable adjustments of the block along the said guide, and an angle member having one arm removably secured to the block and the other arm extending across the slug-guide bracket and having a shock absorbing facing cemented thereto in position for engaging slugs ejected into the bracket to prevent tipping or defacement thereof.

6. A device of the class described comprising an elongated guide member, means to secure said guide member to a type-setting machine adjacent the slug-guide bracket thereof, a block having an opening to receive said guide member with a sliding fit whereby said block may be slid along said guide member, a yieldable pressing member carried by the block and operating to hold said block in its adjusted positions along said guide member, and a member carried by said block in position for extending across the slug-guide bracket to prevent tipping of slugs ejected into the bracket.

HENRY H. COGHILL.
